UNITED STATES PATENT OFFICE

JAMES S. THOMPSON, OF NEW YORK, N. Y., ASSIGNOR TO THE AMERICAN BRAKE SHOE AND FOUNDRY COMPANY, OF WILMINGTON, DELAWARE, A CORPORATION OF DELAWARE

CASTING MOLD

Application filed July 16, 1929. Serial No. 378,717.

This invention relates to casting molds and while it is especially useful in molding railway brake shoes it is not limited thereto but may be used in different forms for making many different kinds of castings.

The invention has for its object, generally, to simplify and improve the means for casting permanent molds whereby the operation is greatly simplified and facilitated and enabled to be carried on with a greater degree of efficiency and at a lower maintenance and operating cost than has been possible heretofore.

More specifically the invention has for its object to provide a permanent mold of relatively light weight and simplicity of construction; to reduce the labor of operating permanent molds; to provide for the use of refractory material in the mold to reduce or to avoid chilling the casting and to protect the metal parts of the mold from the casting heat; to construct and arrange the parts so that the refractory material may be easily replaced as may be required in case of wear or damage or for changing the size or shape of the casting; to provide novel and efficient means for retaining the refractory material in the mold; and generally to improve, lighten and simplify the construction and operation of permanent molds whereby to facilitate the use thereof and reduce the cost of maintenance.

I have illustrated the invention in a selected embodiment in the accompanying drawings wherein,

Fig. 1 is a side elevation of the mold.

Fig. 2 is a top plan view.

Fig. 3 is a sectional view on the line 3—3 of Fig. 2.

Fig. 4 is an elevation at the rear or pivot end of the mold.

Fig. 5 is a sectional view on the line 5—5 of Fig. 1.

Fig. 6 is a sectional detail view showing the interconnection between the refractory and metal parts of the mold.

Referring to the drawings the drag of the mold comprises a pivot or rear end piece 6 and a pouring gate or front end piece 7, said end pieces being recessed to receive a re-

fractory drag section 8, Fig. 3. The drag end pieces are held together on the interposed drag refractory section 8 by tie-rods 9 at the sides of the drag, these tie-rods carrying springs 10 for adjustment and for separating the end pieces to facilitate insertion and removal of the refractory section. This section is retained in place in its proper position in the drag end pieces by soft metal keys 11 which are formed by pouring soft metal into recesses 12 in the end pieces and recesses 13 in the refractory section which register with the recesses 12, Fig. 5. The mold shown in the drawing is made for casting brake shoes of the type which have chilled ends and for this purpose parts 14 of the drag end pieces form end portions of the mold cavity 15 and the refractory section 8 forms a corresponding intermediate portion of the mold cavity. The drag end piece 7 is of skeleton form and adapted to receive the refractory pouring gate 16 which is retained in place on the drag end piece and protected by the holder 17 removably secured to the end piece by bolts 18, Fig. 1. The pouring gate forms a part 16' of the end wall of the mold cavity. A refractory section 19 is held in the drag end piece 6 by soft metal keys 20 like the keys 11 and forms part 19' of the end wall of the mold cavity. The cope comprises a skeleton metal shell 21 which is slidably engaged with and carried bodily by a carrier 22 which is pivoted at 23 on the drag end piece 6. The cope is provided with side ears 24 carrying bolts 25 which operate in slots 26 in the carrier 22. Springs 27 on the bolts bear against the carrier to hold the carrier snugly against the cope. This construction permits the cope to be raised relatively to the other parts of the mold and to be swung with the carrier to open position with the end piece resting upon a suitable support which may form a part of the mold or a part separate therefrom. Handles 28 are provided on the cope for lifting and swinging it. A refractory section 29 is arranged in the cope to co-act with the refractory section 8 for forming the mold cavity 15. This refractory section is held in the cope shell by soft metal keys 30.

corresponding substantially with the keys 11. The refractory 29 has a central opening 31 to receive the attaching lug core 32 which is assembled as a unit insert with the attaching lug 33 and the reinforcing back 34 and is held in the top of the mold cavity against the cope by a looped wire 35. This wire engages the unit insert and passes up through openings 36 in the refractory 29 and over 10 a grooved cam 37 which is supported on a shaft 38 in bearings 39 on a cross piece 40 bolted to the cope shell. The cam is operated by a crank 38' on the shaft 38, and a ratchet 41 also mounted on the shaft 38 is 15 engaged by a pawl 42 pivotally supported on the cross piece 40 for holding the wire taut with the unit insert properly positioned snugly against the cope of the mold. A refractory gate core 43 is held by the pouring 20 gate holder 17 in proper relation with the pouring gate to close the pouring opening 16' except at the bottom thereof where it communicates with the mold cavity, Fig. 3. This gate core is recessed at the bottom at 25 43' to assist in forming the discharge end of the pouring opening. A refractory section 44 is secured in the cope carrier 22 by soft metal keys 45 on opposite sides of the mold, these keys being substantially like the keys 30 11. Brake shoes are provided on the back and at their ends with end lugs and I provide suitably formed refractory sections 46 in the cope to make these end lugs. The ends of the cope refractory section 29 are 35 beveled at 47 and the end lug refractory sections 46 are shaped to engage these beveled surfaces 47. The section 46 adjacent the pouring gate also engages the gate core and the section 46 adjacent the cope carrier 22 40 engages the refractory section 44. These sections 46 rest upon the drag end pieces 6 and 7 above those parts 14 which form end portions of the mold cavity, and they also engage the metal back 34 of the unit insert. 45 The sections 46 are substantially triangular in shape, they are made separate from the section 29 for convenience and so that they can be replaced as required without necessitating replacement of the entire cope refractory. These sections 46 will break down 50 and permit the casting to contract in cooling without damaging the section 29. The beveled surfaces 47 of the section 29 and the correspondingly inclined surfaces of the sections 46 permit the sections 46 to be easily and quickly assembled with the cope in preparing the mold for the casting operation. The drag end pieces are provided with socket lugs 48 on opposite sides to receive the 55 centering pins 49 on the cope for registering the cope properly on the drag.

The invention provides a permanent mold of simple construction and consisting of metal and refractory parts which are assembled with sufficient accuracy and rigidity

for the molding operation and at the same time it has a desirable flexibility which greatly facilitates the manufacture and assembly of the parts and operation of the mold. I have shown the mold adapted for making a railway brake shoe with chilled ends, as heretofore described, and comprising refractory sections suitably disposed for this purpose, but the refractory sections may be made of other shapes and sizes and adapted for molding brake shoes of other kinds or other castings. The refractory material used in casting molds is subjected to liability of more or less damage and resultant waste because of the contraction of the casting in cooling, and my invention provides in a simple way for reducing this waste by providing the refractory sections 46 which will, if necessary, break down to permit contraction of the brake shoe casting lengthwise. 70 The soft metal keys form a convenient and satisfactory means for holding the refractory sections in the mold, they can be easily and quickly applied and they adjust themselves in the process of forming them to 75 effect conditions necessary to hold particular refractory sections in the mold. The refractory sections safe-guard the keys from being affected by the heat of the casting operation. 80 85 90 95 95

I am aware that changes will have to be made in parts of the invention to provide molds for making brake shoes of other kinds and also molds for other castings and I reserve the right to make all such changes that fall within the scope of the following claims. 100

I claim:

1. A casting mold comprising a drag having two end pieces spaced apart, an intermediate member, and means securing said end pieces together and holding the intermediate member in place therebetween. 105
2. A casting mold comprising a drag having two end pieces spaced apart, an intermediate member, and yielding means securing said end pieces together and holding the intermediate member in place therebetween. 110
3. A casting mold comprising a drag having two end pieces spaced apart, an intermediate member, and tie-rods at the sides of said intermediate member and connecting said end pieces and holding the intermediate member in place therebetween. 115
4. A casting mold comprising a drag having two metal end pieces spaced apart, a refractory intermediate member, and means securing said end pieces together and holding the intermediate member in place therebetween. 120
5. A casting mold comprising a drag having two end pieces spaced apart and oppositely recessed, an intermediate member having its ends engaged with said recesses, and means securing said end pieces together and 125 130

holding the intermediate member in place therebetween.

6. A casting mold comprising a drag having two end pieces spaced apart and oppositely recessed, an intermediate member having its ends engaged with said recesses, and tie-rods yieldingly mounted on said end pieces at the sides of said intermediate member and connecting said end pieces and holding the intermediate member in place therebetween.

7. A casting mold comprising a drag having two end pieces spaced apart and oppositely recessed, an intermediate member having its ends projecting into said recesses, and keys interposed between overlapping parts of the end pieces and the intermediate member for securing the intermediate member in place in the end pieces.

20 8. A casting mold comprising a drag having two end pieces spaced apart, an intermediate member, means securing said end pieces together and holding the intermediate member in place therebetween, and a pouring gate supported on one of said end pieces.

9. A casting mold comprising a drag having two end pieces spaced apart, an intermediate member, means securing said end pieces together and holding the intermediate member in place therebetween, a pouring gate supported on one of said end pieces, and a holder secured to said end piece about the pouring gate.

35 10. A casting mold comprising a drag having two end pieces spaced apart, an intermediate member, means securing said end pieces together and holding the intermediate member in place therebetween, and a cope 40 pivotally connected at one end to one of said end pieces.

11. A casting mold comprising a drag having two end pieces spaced apart, an intermediate member, means securing said end pieces together and holding the intermediate member in place therebetween, a carrier pivoted on one of said end pieces, and a cope mounted on said carrier.

50 12. A casting mold comprising a drag having two end pieces spaced apart, an intermediate member, means securing said end pieces together and holding the intermediate member in place therebetween, a carrier pivoted on one of said end pieces, and a cope 55 movable relative to and conjointly with said carrier.

13. A casting mold comprising a drag having two end pieces spaced apart, an intermediate member, means securing said end pieces together and holding the intermediate member in place therebetween, a carrier pivoted on one of said end pieces, and a cope 60 slidably mounted on said carrier to move relative thereto and conjointly therewith.

65 14. A casting mold comprising a drag hav-

ing two end pieces spaced apart, an intermediate member, means securing said end pieces together and holding the intermediate member in place therebetween, a carrier pivoted on one of said end pieces and having parallel vertical slots therein, a cope, and means on said cope and operating in said slots for connecting the cope to the carrier to move relative thereto and conjointly therewith.

70 15. A casting mold comprising a drag having two end pieces spaced apart, an intermediate member, means securing said end pieces together and holding the intermediate member in place therebetween, a carrier pivoted on one of said end pieces and having parallel vertical slots therein, a cope, and yielding means on said cope and operating in said slots for connecting the cope to the carrier to move relative thereto and conjointly therewith.

75 16. A casting mold comprising a drag having two end pieces spaced apart, an intermediate member, means securing said end pieces together and holding the intermediate member in place therebetween, a carrier pivoted on one of said end pieces and having parallel vertical slots therein, a cope, bolts on the cope projecting laterally through said slots for connecting the cope to the carrier to move relatively thereto and conjointly therewith.

80 17. A casting mold comprising a drag having two end pieces spaced apart, an intermediate member, means securing said end pieces together and holding the intermediate member in place therebetween, a carrier pivoted on one of said end pieces and having parallel vertical slots therein, a cope, bolts on the cope projecting laterally through said slots for connecting the cope to the carrier to move relatively thereto and conjointly therewith, and springs on the bolts bearing against said 85 carrier to yieldingly hold the cope and carrier in abutting relation.

100 18. A casting mold comprising a skeleton shell, a cope having a section arranged in said shell and forming a wall portion of the mold cavity, and keys engaging opposite walls of said shell and section and holding the section in said shell.

110 19. A casting mold comprising a skeleton shell, a cope having a section arranged in said shell and forming a wall portion of the mold cavity, and end blocks engageable with said section and also forming wall portions of the mold cavity.

115 20. A casting mold comprising a skeleton shell, a cope having a section arranged in said shell and forming a wall portion of the mold cavity, and frangible end blocks engageable with said section and also forming wall portions of the mold cavity.

120 21. A casting mold comprising a skeleton shell, a cope having a section arranged in said shell and forming a wall portion of the mold cavity, said section having beveled ends, and end blocks shaped to engage said beveled ends

- and also forming wall portions of the mold cavity.
22. A casting mold comprising a shell, a cope having a refractory section arranged in said shell and forming a wall portion of the mold cavity, and separate refractory blocks at the ends of said section and also forming wall portions of the mold cavity.
23. A casting mold comprising a shell, a cope having a refractory section arranged in said shell and forming a wall portion of the mold cavity, and separate refractory blocks forming wall portions of the mold cavity, said blocks being recessed to receive parts of the casting and adapted to break down to accommodate contraction of the casting in cooling without affecting other parts of the mold.
24. A casting mold comprising a drag having two end pieces spaced apart, an intermediate member, means securing said end pieces together and holding the intermediate member in place therebetween, a carrier pivoted on one of said end pieces, a pouring gate supported on the other end piece, and a cope mounted on said carrier to move independently thereon between the carrier and the pouring gate and to swing conjointly with the carrier.
25. A casting mold comprising a drag having two end pieces spaced apart, a refractory intermediate member, means securing said end pieces together and holding the intermediate member in place therebetween, said end pieces and intermediate member forming wall portions of the mold cavity, a refractory section on one end piece and a refractory pouring gate on the other end piece forming end wall portions of the mold cavity, and a cope comprising a refractory section forming a wall portion, and end blocks separate from but cooperating with said refractory section and forming wall portions of the mold cavity.
26. A casting mold comprising a drag and a cope having a mold cavity therein, means for holding an insert in said mold cavity to be embedded in the casting, said means comprising a looped wire engaging the insert and passing through the cope, a rotatable shaft having an eccentric thereon about which said loop may be passed, and pawl and ratchet means cooperating with said shaft whereby when said shaft is rotated to move said eccentric to tighten said loop said shaft will be held against unloosening movement.
27. A casting mold comprising a drag and a cope, said drag and cope having metal and refractory parts providing a mold cavity, portions of said metal parts being disposed about said refractory parts whereby portions of the surfaces of said parts will be disposed in opposition to each other, the opposite surfaces of said parts having cooperating recesses therein, and soft metal keys
- in said cooperating recesses for connecting said refractory parts to said metal parts.
28. A casting mold comprising a drag and a cope, said drag and cope having metal and refractory parts providing a mold cavity, portions of said metal parts being disposed about said refractory parts whereby portions of the surfaces of said parts will be disposed in opposition to each other, the opposite surfaces of said parts having cooperating recesses therein, and keys cast in said cooperating recesses for connecting said refractory parts to said metal parts.
- Signed at New York, State of New York, United States of America, this 3rd day of July, A. D., 1929.
